UNITED STATES PATENT OFFICE.

PATRICK P. LA MONTAGNE, OF BOURBONNAIS, ILLINOIS, ASSIGNOR TO PARAMOUNT KNITTING COMPANY, OF CHICAGO, ILLINOIS, A CORPORATION OF ILLINOIS.

KNITTING-MACHINE.

1,325,158.

Specification of Letters Patent. Patented Dec. 16, 1919.

Application filed December 7, 1917. Serial No. 205,980.

To all whom it may concern:

Be it known that I, PATRICK P. LA MONTAGNE, a citizen of the United States, residing at Bourbonnais, county of Kankakee, State of Illinois, have invented an Improvement in Knitting-Machines, of which the following description, in connection with the accompanying drawing, is a specification, like characters on the drawing representing like parts.

This invention relates to knitting machines particularly that type employing separate latch needles and has for its main object the provision of means for insuring the positioning of the yarn in the path of the needle so that it will be caught by the hook and covered by the latch.

The invention also has for its object more specifically to provide bur wheels coöperating with the dial and cylinder needles respectively of a knitting machine and acting to position the yarn in the needle so that it will be caught by the hooks and covered by the latches.

The invention also has for its object to provide a particular form and construction of bur wheel for so properly positioning the yarn.

The invention also has for its object to provide a bur wheel working in conjunction with a set of separate latch needles and acting to position the yarn properly in the needles.

The invention also has for its object to provide for the construction and location of a pair of bur wheels one coöperating with a set of cylinder needles and the other coöperating with a set of dial needles so that the bur wheels may be placed as close together as possible and adjacent the knitting point.

The invention also has for its object to provide a bur wheel construction in connection with a knitting machine knitting the so-called French welt.

These and other objects of the invention will appear more fully from the accompanying description and drawings and will be particularly pointed out in the claims.

A construction embodying the invention is particularly useful in connection with a knitting machine of the circular type ar-

ranged for knitting the so-called French welt and consequently a preferred form of the invention is herein shown embodied in such a machine. An example of a machine for knitting the French welt is found in the patent to Wildman *et al.* No. 1,047,355, granted December 17, 1912, and a machine of that construction is shown in the drawings together with a preferred form of the present invention embodied therein.

In the drawings,

Fig. 1 is a plan view of the knitting head of the machine;

Fig. 2 is a view chiefly in central vertical cross section of a portion of the knitting head showing the bur wheel for the dial needles in working position;

Fig. 3 is a diagrammatic view showing a pair of cylinder needles and a pair of dial needles engaged in knitting the French welt with the yarn just having been fed to the dial needles;

Fig. 4 is a view similar to Fig. 2 showing the bur wheel for the cylinder needles in working position;

Fig. 5 is a side elevation showing the relative positions of the two bur wheels and thread guide when both bur wheels are in working position together;

Fig. 6 is a detail in horizontal cross section showing the relation of the cylinder bur wheel, a cylinder needle and the yarn;

Fig. 7 is a detail in plan and cross section showing the position of the dial needles when taking the yarn.

Fig. 8 is a view in front elevation of a portion of the machine showing the position of the dial needle bur wheel in relation to the needles.

The general construction and operation of the knitting machine herein disclosed in illustrating the present invention being well known and familiar and being fully set forth in the aforesaid patent to Wildman *et al.* No. 1,047,355 need not be here described in detail. The construction and operation of the separate latch needles herein illustrated is also well known and familiar. The type of separate latch dial needles employed is disclosed in the patent to Pope and Randall No. 1,241,882 granted October 2, 1917, and the cylinder needles are generally simi-

lar to those disclosed in the patent to Pope and Randall No. 1,096,945 granted May 19, 1914.

In knitting machines employing the ordinary type of pivoted latch needles the hook is constructed so as to be entirely in front of the body of the needle thereby making it possible to feed the yarn directly into the path of the descending hook with the ordinary method of feeding, and in the knitting machines employing the spring beard needle the yarn is moved up beneath the beard of the needle so as to come within the hook. When, however, the knitting machine employs the separate latch type of needle wherein the latch member reciprocates longitudinally with respect to the hook member in effecting the opening and closing movements of the needle there is nothing in the needle structure or its operation which insures the yarn being properly positioned and being covered by the latch prior to casting off. This invention therefore provides means, preferably the bur wheels herein disclosed, for insuring the proper positioning of the yarn in the case of the separate latch needle.

When a circular knitting machine having a set of dial needles and a set of cylinder needles is employed in such work as the knitting of the so-called French welt there are at least two yarn feeds. At one side of the machine the dial needles take no part in the knitting operation and the cylinder needles knit a plain web while at the other side of the machine the cylinder needles take no part in the knitting operation and the dial needles knit a plain web so that two plain webs are being knit upon the machine and these, when the conjoint action of the two sets of needles is resumed, are united and form the desired welt. In the case of a machine employing separate latch needles for performing this class of work there is a peculiar tendency for the yarn to fail to be caught by the dial needles because at the point where the dial needles are knitting the cylinder needles are not acting upon the yarn and consequently do not draw the yarn down over the dial needles and consequently into position. The present invention is therefore of particular value in insuring the yarn being properly positioned in the dial needles in this type of machine.

The machine illustrated so far as is of interest in connection with the present invention comprises a cylinder 1 held against rotation, a cylinder cam carrier 2 rotarily mounted concentric of the cylinder and provided with suitable cylinder needle operating cams 3 and 4. The exterior of the cylinder is provided with the superimposed grooves 5 and 6 in which are mounted respectively the hook members 7 and latch members 8 of the separate latch needles.

The hook member 7 of the needle is provided with the usual butt 9 coöperating with the cams and is longitudinally slotted at its upper end. The latch member, the shank of which rides in the groove 6 has a head 10 mounted to move through the slot in the hook member to bring the latch point 11 into and out of coöperation with the hooked end of the hook member. In the construction illustrated the latch member 7 is further provided with an arm 12 extending over the face of the hook member and acting to prevent the latch member from swinging so far inwardly as to cause the point of the latch to pass back of the hook member. In this construction the reciprocation of the hook member effects the required reciprocation of the latch member through the coöperation of the shouldered head of the latch member and the ends of the longitudinal slot in the hook member all as set forth in the patents above referred to. The cams for operating the cylinder needles may otherwise be of the general construction and operation disclosed in the aforesaid patent to Wildman.

The knitting machine further comprises a dial stud or shaft 13 carrying the dial bed 14 having the superimposed grooves 15 and 16. The separate latch dial needles mounted in the superimposed grooves may be of the construction shown in the patent to Pope and Randall No. 1,241,882 above referred to and comprise a hook member 17, a latch member 18, and a frictional spring member 19. The hook member is provided with the usual butt 20 coöperating with the dial cams 21 and 22 which are rotarily mounted with respect to the stud 13 and which may be otherwise of the general construction and operation disclosed in the above mentioned patent to Wildman, *et al.*

The machine which is generally the same as shown in the above mentioned patent to Wildman *et al.* is provided with two yarn feeds arranged substantially diametrically opposite and consequently the cams are arranged to cause the needles to knit at two diametrically opposite points. Consequently, as illustrated, the cams, the means for operating the cams, and the parts with which this invention is particularly concerned are duplicated at opposite points on the machine. For convenience of illustration, however, the features in which a preferred form of this invention is shown embodied are illustrated at but one side of the machine.

One of the yarn feeds is shown in Fig. 8 wherein a bracket 23 projects from the dial cam carrier 24 and is provided with an adjustable depending guide arm 25. The yarn 26 is delivered from the supply through a guide eye 27 to a guide eye 28 at the lower end of the arm 25.

The foregoing description will be sufficient in connection with the aforesaid patent to Wildman *et al.* to make clear the general construction and operation of a circular type of knitting machine adapted for knitting a French welt and fitted with the separate latch type of needle.

The means for insuring the proper positioning of the yarn in the needles of this invention is preferably embodied in one or more bur wheel mechanisms. These mechanisms are particularly useful in connection with the dial needles for the reasons already noted and are preferably employed also in connection with the cylinder needles and when the yarn is provided with more than one feed the latter mechanism is duplicated and in each case operated in a similar manner.

Referring first to the bur wheel provided for the dial needles and to the particular construction herein illustrated as a preferred embodiment of the invention, there is provided a bur wheel support 29 preferably pivotally mounted on the cam carrier 2. For this purpose a bracket 30 is secured to the cam carrier 2 and to this bracket 30 the bur wheel support 29 is pivoted by the screw 31 so that the support may swing toward and from the center of the machine. A journal bracket 32 is adjustably secured to the support 29 by a set screw 33. In this journal bracket 32 is journaled the bur wheel shaft 34 which at its inner end carries the bur wheel 35. A spring 36 connecting the bur wheel support 29 and the bracket 30 acts to hold the bur wheel yieldingly in position so that it may swing away from the work if any obstruction is met. The entire bur wheel and support may also be swung out of position by swinging it about the pivot 31.

The bur wheel 35 has the general shape of a truncated cone with its periphery presenting alternating longitudinal ribs 37 and grooves 38. The bottoms of the grooves 38 extend parallel to the axis of the bur wheel and the ribs 37 are flared radially at 39 toward the base.

When the bur wheel is swung into working position the shaft 34 extends radially of the machine and the bur wheel rests over the faces of the dial needles when in their yarn-receiving position, the ribs and grooves on the bur wheel being spaced to correspond with the spacing of the needles so that the bur wheel is in mesh with the needles. The juncture of the flared portion of the ribs with the straight portion of the ribs forms an angle which is so positioned as to receive the yarn from the feed and deliver it in proper relation to the hooks of the needles.

It will be seen that since the bur wheel and the dial needle bed have a relative bodily transverse or rotary movement and since the bur wheel is in mesh with the dial nee-

dles that the bur wheel will be rotated by the dial needles. As it is thus rotated and the yarn is fed beneath its periphery the yarn will be depressed by the ribs 37 of the bur wheel between the dial needles and thus be forced down into the path of the hooks as shown in Fig. 8. As the needles retract and the hooks catch the yarn and carry it inwardly the yarn will draw down under the flared portion 39 of the ribs 37 of the bur wheel and thus be still more surely forced into the hooks. By the time that the hook members have retracted sufficiently to clear the bur wheel the latches will have closed over the hooks and will thus retain the yarn in position.

The cylinder bur wheels are mounted and operate on the same general principle. In the construction illustrated more particularly in Fig. 4 a bracket 40 is secured to the cam carrier 2, a cylinder bur wheel supporting arm 41 is pivotally mounted by the stud 42 to this bracket and is provided with a depending tail 43 abutting an adjustable screw 44 mounted in the bracket by which the arm 41 is adjusted on its pivot. This arm is grooved on its upper face to receive a slide bar 45 held in place by a headed screw 46 passing through a slot in the bar 45. This slide bar 45 is yieldingly projected toward the center of the machine by a helical spring 47 connected at one end thereto and at the other end to the arm 41 and the forward limit of its projection is adjustable by the screw 48 threaded into the bar 45 and abutting the end of the arm 41. The slide bar 45 has secured thereto at its forward end the journal bracket 49 in which is vertically journaled the bur wheel shaft 50 and on the lower end of which is mounted the cylinder bur wheel 51. It will thus be seen that the cylinder bur wheel is yieldingly held in position and may yield away from the needles, that it is adjustable bodily with respect to the needles, and that it may be thrown entirely out of position by being swung about the pivot 42.

The cylinder bur wheel coöperates with the cylinder needles in a generally similar manner to that of the dial bur wheel and dial needles. The cylinder bur wheel likewise has the general shape of a truncated cone with its periphery presenting alternating longitudinal ribs 52 and grooves 53 meshing with the cylinder needles. The ends of the ribs flare radially outwardly toward the base of the bur wheel and at the base of the flaring portion a circumferential groove 54 extends through the ribs and serves to receive the yarn from the feed.

The bur wheel is so positioned that when the cylinder needles are in yarn-receiving position and the yarn is fed to the groove 54 the yarn will be laid in proper relation to the hook and will be depressed by the ribs

between the needles so that as the hook members of the needles retract they will catch the yarn and the radial ends of the ribs will still further force the yarn into position, and 5 as the hook leaves the bur wheel in its retracting movement the latch will come into position over the hook and retain the yarn in place.

The peculiar tapering or truncated conical 10 shape of the two bur wheels and the relation of the bur wheels at right angles to each other enables them to be located closely adjacent each other and closely adjacent the knitting point. This relation is shown in 15 the two views Fig. 1 and Fig. 5 wherein it will be seen that the bur wheels overlap as it were in both directions thus enabling the peripheries to be placed closely adjacent.

In knitting the French welt where the dial 20 needles knit at one side of the machine with the cylinder needles out of action and the cylinder needles knit on the other side of the machine with the dial needles out of action the cylinder bur wheel at the first side of the 25 machine and the dial needle bur wheel at the opposite side of the machine preferably remain in mesh and are idly rotated by the retracted needles and are thus ready to resume their functions whenever required. 30 When, however, both sets of needles are in operation as in the knitting of ribbed work then both cylinder bur wheels will function and the dial bur wheel although rotating will have no function. When the French 35 welt is being knit the dial bur wheel functions and the yarn extends from the yarn guide into the circumferential groove of the cylinder bur wheel and thence underneath the dial bur wheel.

40 This invention by combining a bur wheel with a set of separate latch needles insures the proper positioning of the yarn in the hook members of the needles until the hook members can be closed over by the latch 45 members. This invention also in the particular forms of bur wheel disclosed presents a construction peculiarly adaptable for securing the desired results.

Having fully described my invention, 50 what I claim as new and desire to secure by Letters Patent is:

1. In a knitting machine the combination 55 of a set of separate latch needles, means for reciprocating said needles and effecting the relative coöperating movements of the members thereof, and a rotatable toothed bur wheel intermeshing with said needles when in yarn-receiving position, rotated by relative movement therewith, and acting to insure the yarn being caught thereby.

2. In a knitting machine the combination 60 of elements specified in claim 1 in which the axis of rotation of the bur wheel is substantially parallel with the path of the needle 65 opposite the bur wheel, in which the bur

wheel has the general shape of a truncated cone, and in which the bottoms of the grooves between the teeth extend parallel to the axis of the bur wheel.

3. In a knitting machine, a dial, a set of 70 separate latch needles mounted for radial reciprocation therein, means for reciprocating said needles and effecting the relative coöperative movements of the members thereof, a toothed bur wheel rotatably 75 mounted on an axis radial to the dial with its teeth in mesh with the needles and bodily revolvable with respect to the dial, whereby the said bur wheel is rotated by the needle and acts to insure the yarn being caught 80 thereby.

4. In a knitting machine, a dial, a set of 85 separate latch needles mounted for radial reciprocation therein, means for reciprocating said needles and effecting the relative coöperative movements of the members thereof, a rotatable toothed bur wheel intermeshing with said dial needles when in yarn receiving position, rotated by relative movement therewith, and acting to insure the 90 yarn being caught thereby, a set of cylinder needles and means for reciprocating said needles, and means causing the two sets of needles to knit in conjunction or separately as desired whereby when the dial needles are 95 knitting separately the bur wheel acts to insure the yarn being caught thereby.

5. A knitting machine comprising a set of 100 separate latch needles, means for reciprocating said needles, means for feeding yarn to the face of said needles, a rotatable toothed bur wheel having the general shape of a truncated cone and provided with a circumferential peripheral groove near its base, the 105 said bur wheel being supported at the knitting point with its teeth projecting between the needles, with its groove in line with the yarn feed, and with its base facing the retracted position of the needles, and means for giving a relative lateral movement to 110 said needles and said bur wheel, whereby the bur wheel is rotated by the needles to lay the yarn lying in its groove in the path of the needles, and whereby as the needles retract the yarn is forced back between the 115 needles insuring its being caught by the hooks.

6. A knitting machine comprising a dial, 120 a set of dial needles radially reciprocable therein, a cylinder, a set of cylinder needles reciprocable therein, a rotatable toothed dial bur wheel having the general shape of a truncated cone resting over the dial needles 125 when in projected position and intermeshing therewith, and a rotatable toothed cylinder bur wheel having the general shape of a truncated cone and having the intermediate portion of its periphery closely adjacent to the intermediate portion of the periphery of the dial bur wheel and resting against the 130

cylinder needles when in projected position and intermeshing therewith whereby the yarn may be delivered from the respective bur-wheels to their respective needles closely adjacent to the knitting point.

7. A bur wheel for knitting machines having the general shape of a truncated cone with its periphery presenting alternating longitudinal teeth and grooves and having a circumferential groove intersecting said teeth.

8. A bur wheel constructed as set forth in claim 7 in which the teeth are flared radially outward from the said circumferential groove to the base.

9. A bur wheel constructed as set forth in

claim 7 in which the longitudinal grooves at their bottoms extend parallel to the axis of the bur wheel.

10. A bur wheel for knitting machines 20 having the general shape of a truncated cone with its periphery presenting alternating longitudinal teeth and grooves and having the teeth flared radially outward toward the base.

11. A bur wheel constructed as set forth in claim 10 in which the longitudinal grooves at their bottoms extend parallel to the axis of the bur wheel.

In testimony whereof, I have signed my 30 name to this specification.

PATRICK P. LA MONTAGNE.
